ATTORNEYS

UNITED STATES PATENT OFFICE.

JOHN M. YOUNG, OF BROOKLYN, NEW YORK, ASSIGNOR TO AMERICAN CAN COMPANY, OF NEW YORK, N. Y., A CORPORATION OF NEW JERSEY.

KEY-OPENING CAN.

Application filed January 15, 1923. Serial No. 612,602.

To all whom it may concern:

Be it known that I, JOHN M. YOUNG, a citizen of the United States, residing in Brooklyn, in the county of Kings and State 5 of New York, have invented a new and useful Improvement in Key-Opening Cans, of which the following is a specification.

My invention relates to an improvement in key opening cans intended primarily to provide a suitable means of retaining the key upon the can prior to use, while 10 also permitting ready removal by the customer.

To this end, the invention contemplates 15 the provision of a key having a suitable part thereof welded to the can and notched, or otherwise weakened, adjacent the point of welding whereby it may be readily removed by a fracture at the notch.

20 Other objects and advantages of the invention will be apparent as it is better understood from the following description, which, taken in connection with the accompanying drawings, discloses a preferred embodiment thereof.

Referring to the drawings,

Figure 1 is a perspective view of a key opening can having a key attached thereto in accordance with my invention;

30 Fig. 2 is a plan view thereof with the key in normal attached position; and

Figs. 3 and 4 are similar views showing the different positions of said key as it is being removed.

35 I have shown on the drawings, for the purpose of illustrating my invention, a can having a cylindrical body 11 with the usual bottom 12 and cover 13 permanently attached thereto by a double seam, or other

40 hermetic joint. A tearing strip 14 is set off in the cylindrical body 11 by means of parallel score lines 15 and 16. Said strip is provided with an extension, or tongue, 17 adapted to be engaged by a slotted key upon 45 which the strip may be wound as it is torn away. Said tongue preferably takes off from the body at the side seam 18 in which the body edges are joined together, being merely a projection of the body material at 50 one edge.

A key 19, having a slotted body 21 and a head or finger piece 22, is spot welded at 23 to the can cover 13. The key material at this point is somewhat flattened and the

welding holds it firmly in place. Adjacent 55 the spot weld, the key wire is notched, as at 24, and thus weakened so that pressure applied to the body, to turn it upon the cover, readily fractures the wire at the notch and the key is thus removed for use. This action is clearly illustrated in Figs. 3 and 4, from which it will be seen that the notch is first widened, as shown at 25 in Fig. 3, and then the wire is severed as shown in Fig. 4, leaving the welded portion 26 at- 60 65 tached to the cover.

Since the key is firmly held in flat condition against the cover, which has an outer upstanding rim 27, it is protected 70 against accidental removal and still may be readily broken away by moderate pressure applied in the right manner by the user. Thus it will always be present when needed, with no attendant difficulties in removing it for use. 75

It is thought that the invention and many of its attendant advantages will be understood from the foregoing description, and it will be apparent that various changes may be made in the form, construction and 80 arrangement of the parts without departing from the spirit and scope of the invention, or sacrificing all of its material advantages, the form hereinbefore described being merely a preferred embodiment thereof. 85

I claim:

1. A key opening can, having a key welded thereto, said key being notched beyond the point of welding whereby it may be removed by fracture of the notch. 90

2. A key opening can, having a key welded thereto, said key being notched adjacent the point of welding whereby it may be removed by fracturing pressure exerted at an angle to the notch. 95

3. A key opening can, and a key fixedly secured thereto at a given point in the key body, the material of said key being weakened adjacent said point whereby the key may be broken away for use. 100

4. A key opening can, and a wire key having an end portion thereof spot welded thereto, the wire being cut away near the point of weld and readily severable by pressure exerted by the hand. 105

5. A key opening can, and a wire key formed with a tongue-engaging body and a head portion curved to an extremity ad-

jaçent said body, said extremity being flattened and welded to the can cover and the material adjacent said welded extremity being notched whereby it may be fractured by rotary pressure on the body of the key.

6. A key opening can, comprising a body provided with a tearing strip, a cover, and

a key having an end portion welded to said cover, the material of said key being weakened adjacent the point of weld and adapted to be fractured by moderated turning pressure applied to the key.

JOHN M. YOUNG.
